U. Grant Hayden
ATTORNEY

UNITED STATES PATENT OFFICE.

CLARENCE D. KIRTLAN, OF WOODLAKE, CALIFORNIA, ASSIGNOR OF TWO-FIFTHS TO
GILL HUMBERGER, ONE-TENTH TO JOHN HUMBERGER, AND ONE-TENTH TO LESTER
HUMBERGER, ALL OF VISALIA, CALIFORNIA.

VALVE-SPRING COMPRESSOR.

Application filed March 15, 1927. Serial No. 175,452.

My invention consists of an improved tool for use in the handling of the spring which is used to hold the valve shut in all 5 poppet valve internal combustion engines. The springs are spiral in shape. Much difficulty is experienced by mechanics in compressing such springs, as the same must be compressed, whenever the pin at the end of the valve stem is removed to allow the removal or replacing of the valve.

The object of my invention is to provide a tool which will fit all sizes of springs, which is quick and positive in its operation, and simple and economic in construction.

The tool consists of four long arms, 6 and 7; two above and two below and all hinged together at one end and each having a jaw on the outer end, 10, 11, 12 and 13, shaped to squeeze in between the coils of the spring 20 and to hold the spring both upon the end and sideways, and also a tubular handle, 8, which when pushed over the hinged end of the arms toward the jaw ends brings the jaws together from all directions compressing and clamping the spring.

Figure 1 is a side view of the arms as used in connection with a spring. Figure 2 is a top view of the same. Figure 3 is a detached sectional view of the tubular handle 30 and Figure 4 is a side view showing a spring compressed with the tubular handle pushed on over the arms.

The spiral spring, 5, and the washer, 14, always found at one end of such springs, are 35 no part of the tool.

The arms 6 and 7 may be of any strong metal but preferably of smooth round steel. They are in pairs, the upper pair clamping the top and sides, and the lower pair clamping 40 the bottom and sides of the spring. They may be hinged or fastened together at point 16, 17, in any manner, bolted or one coiled around the other as 6 is shown coiled around 7 at point 16. The jaw ends of the arms 45 must each be curved in three directions. First, with an outward curve, 10, to approximate the form of the spiral spring and so that the arm will push against the front of the spring when the tubular handle is being 50 pushed on over the arms to contract the jaws and compress the spring, and second, with an upward or a downward curve, 11, so as to bring the jaw arm along beside two

or more of the coils of the spring, thereby clamping the side of the spring to prevent 55 it from bulging out, and third, with a right or left inward turn to bring the extremity of the upper arms over the top of an upper coil of the spring and the extremity of the lower arms under the bottom of a lower coil 60 of the spring. The tip of the jaws, 12, 13, should be flattened, the more easily to be inserted between the coils of the spring.

At point 9 a hole is shown through the tubular handle through which a bolt or cotter 65 pin may be inserted to prevent separation of the two parts of the tool when not in use and also to assist in pulling the jaws out from the spring when the handle is pulled back.

What I claim as new and desire to secure by Letters Patent, is:—

1. A valve spring compressor having four arms fastened together at one end, and each terminating at the other end in a curved 75 jaw, the upper right jaw being curved outward then upward before turning to the left inward to hook over the upper side of a coil of a spring, and the inward turn or hook of the end of each arm being just long enough 80 to keep the spring coils from slipping past it, the lower right jaw being curved outward then downward before turning to the left inward to hook over the lower side of a coil of a spring, the upper left jaw being curved 85 outward then upward before turning to the right inward to hook over the top of a coil of a spring, the lower left jaw being curved outward then downward before turning to the right inward to hook over the lower side 90 of a coil of a spring, each outward curve being concaved to approximate the circle of the coils of a valve spring, and means for pressing the four arms toward each other, substantially as shown.

2. A valve spring compressor having four arms fastened together at one end, and each terminating at the other end in a curved jaw, the upper right jaw being curved outward then upward before turning to the left inward to hook over the upper side of a coil of a spring, the lower right jaw being curved outward then downward before turning to the left inward to hook over the lower side of a coil of a spring, the upper left jaw being curved outward then upward before 100 105

turning to the right inward to hook over the top of a coil of a spring, the lower left jaw being curved outward then downward before turning to the right inward to hook over the lower side of a coil of the spring, each outward curve being concaved to approximate the circle of the coils of a valve

spring, and a tubular handle of proper size to push on over the arms and press them toward each other, substantially as shown. 10

In witness whereof, I have hereunto subscribed my name.

CLARENCE D. KIRTLAN.
